CLAIM

The ornamental design for a barstool, as shown and described.

DESCRIPTION

FIG. 1 is a front perspective view of a barstool showing our new design;

FIG. 2 is a right side view thereof, with the left side being a mirror image;

FIG. 3 is a top view thereof;

FIG. 4 is another front perspective view thereof; and,

FIG. 5 is a bottom view thereof.

The broken lines shown in the drawings depict portions of the barstool that form no part of the claimed design.

1 Claim, 5 Drawing Sheets
